UNITED STATES PATENT OFFICE.

RUDOLPH ZAKRZEWSKI AND KAZIMIEZ SULEK, OF THORPE, WEST VIRGINIA.

FIRE-ALARM BOX.

Application filed October 22, 1921. Serial No. 509,491.

To all whom it may concern:

Be it known that we, (1) RUDOLPH ZAKRZEWSKI and (2) KAZIMIEZ SULEK, (1) a citizen of the United States of America and (2) a citizen of Poland, residing at Thorpe, in the county of McDowell and State of West Virginia, have invented certain new and useful Improvements in Fire-Alarm Boxes, of which the following is a specification.

This invention relates to certain new and useful improvements in fire alarm boxes particularly of that type embodying means only releasable by an authorized person for catching and holding the arm of a person turning in an alarm so that if such person turns in a false alarm, he will be taken into custody and be given proper legal punishment.

The primary object of the invention is to generally simplify and improve devices of this kind.

Another object of the invention is to provide an alarm box including a receptacle into which the hand of a person must be inserted for turning in an alarm and wherein the hand-hold is provided with a closure, the opening of which automatically causes sounding of an alarm at the proper places such as police precincts, houses and the like.

Still another object of the invention is to provide within the fire alarm box a switch mechanism adapted to render the alarm operative upon turning movement and to simultaneously release a spring pressed arm engaging member which is normally urged to arm-engaging position across the hand-hold of the alarm box, and means being provided to automatically engage the arm-engaging member to retain the same in arm-engaging position.

A still further object of the invention is to provide an improved mechanism adapted to be key-actuated by an authorized person to first release the retaining means for the arm-engaging member and to then retract the arm-engaging member to inoperative position.

With the above general objects in view and others that will appear as the nature of the invention is better understood and the invention consists in the novel form, combination and arrangement of parts herein-after more fully described in connection with the accompanying drawings, in which like characters of reference indicate corresponding parts throughout the several views.

In the drawings,

Figure 1 is a front elevational view of an alarm box constructed in accordance with the present invention,

Figure 2 is a view of the device shown in Figure 1 with one of the side walls removed, and parts within the casing in side elevation,

Figure 3 is a horizontal sectional view taken substantially upon line III—III of Figure 2,

Figure 4 is a vertical sectional view taken upon line IV—IV of Figure 2 with the arm-engaging member in inoperative position,

Figure 5 is a view similar to Figure 4 with the arm engaging member in operative position,

Figure 6 is a vertical sectional view taken upon line VI—VI of Figure 3,

Figure 7 is a fragmentary sectional view taken upon line VII—VII of Figure 2, and

Figure 8 is a side elevational view of the form of key for releasing and resetting the arm-engaging member.

Referring more in detail to the several views, the present invention embodies a casing 5 preferably of rectangular form with a front wall thereof formed with a central hand-hold or opening 6 which is normally closed by a laterally swinging closure disk 7 hinged as at 8 to the front wall of the casing 5 interiorly of the latter so that the same may be swung downwardly as indicated by dotted lines in Figure 1 to open position, the closure disk 7 being provided with any suitable form of operating knob or handle 9 extending outwardly through the opening 6 and the front wall of the casing 5 being provided with a slot communicating with the opening 6 as at 10 into which the knob or handle 9 may move when the closure disk 7 is opened.

A vertical transverse partition 11 is fixed within the casing 5 adjacent to and parallel with the front wall of said casing so as to define a narrow compartment 12 in the lower portion of which is mounted a suitable normally open circuit closer 13, one contact of which is connected by means of a wire 14 with a suitable source of electricity 15, the other side of which is connected by a wire 16 with a suitable alarm 17 which may be located at the proper point such as a fire engine house and which has its other side connected by a wire 18 with the other contact of the circuit closer 13. A lug 19 is

- provided upon the inner face of the closure disk 7 in such position as to engage the outer flexible contact of the circuit closer 13 for pressing said flexible contact into engagement with the stationary contact thereof so that the alarm 17 will be caused to operate upon opening of the closure disk 7. This alarm 17 is preferably of an audible kind such as an electric bell.
- 10 A tube 20 is fixed horizontally within the casing 5 so as to extend from the rear wall of said casing to a point slightly spaced from the partition 11 and with the bore of said tube alined and concentric with the hand-hold 6 and suitably mounted upon the inner face of the rear wall of the casing 5 centrally within the tube 20 is a suitable rotary electric snap switch 21 of any usual or preferred type involving a handle 22 adapted to be turned clockwise. The switch 21 may control an alarm circuit including wires 23 and 24, a source of electricity 25 and an alarm 26 preferably in the form of a visible indicator or incandescent lamp, which lamp will show that the person turning in the alarm has inserted his arm into the casing a sufficient distance to have been caught by the arm-engaging member as will presently appear.
- 15 20 The rotatable handle 22 of the switch 21 has an arm 27 fixed thereto and the arm 27 has one end of a link 28 pivoted to the outer end thereof, which link 28 extends upwardly through an opening 29 provided in the tube 6 adjacent the rear wall of the casing 6 and has its upper end pivoted as at 30 with an arm 31 suitably fixed upon a horizontal longitudinal shaft 32 which is suitably rotatably mounted in the casing 5 and which 35 extends from the rear wall of the casing to the partition 11. The shaft 32 has another arm 33 fixed thereon adjacent the partition 11 inwardly of the latter and this arm 33 depends and has its lower end pivotally connected to one end of a link 34 which has its other end pivoted to the lower end of a resilient catch 35 as at 36. The resilient catch 35 is preferably mounted upon the inner face of the partition 11 and 40 includes a shouldered portion 37 behind which is adapted to engage the upper end of a pivoted arm-engaging member 38 which is preferably of curved form as shown and attached to the inner face of the partition 11 below the opening 6 by a pivot pin 39. Any suitable means such as a leaf spring 40 may be provided for normally urging the arm engaging member 38 across the opening 6 toward a fixed arm engaging member 41 45 suitably attached to the partition 11 at the opposite side of the opening 6.
- A rigid member 42 is pivoted as at 43 on the partition 11 above the opening 6 with its teeth directed downwardly so as to engage a lateral tooth 44 provided upon the

upper end of the arm-engaging member 38 whereby swinging of the arm-engaging member 38 back to its released position will be prevented until the retaining member 42 is raised to disengage its teeth from the tooth 44. A leaf spring 45 may be provided for holding the retaining member 42 with its teeth engaging the tooth 44.

A rod 46 is mounted for vertical sliding movement near the stationary arm-engaging member 41 and has a hooked upper end engaging a similarly formed end upon the retaining member 42 as at 47 so that upon downward movement of the rod 46, the retaining member 42 is caused to raise against the action of the spring 45 so as to disengage from the tooth 44. The front wall of the casing 5 and the partition 11 are provided with alined keyholes 48 adapted to permit the insertion of a key 49, the form of which is clearly shown in Figure 8. As shown, this key involves the usual stem and handle with a bib 50 at the inner end of the stem of relatively great length and reduced for a portion of its length from the outer end inwardly so as to provide stepped shoulders 51 and 52.

The slideable rod 46 is provided with a lateral lug or extension 53 disposed directly beneath the keyhole of the partition 11 so as to be engaged by the shoulder 52 when the key is turned so that said key will cause downward movement of the rod 46 for disengaging the retaining member 42 from the tooth 44.

The arm-engaging member 38 is extended downwardly beyond the pivot pin 39 where it is formed with a hooked end 54 engaging in a similarly formed end 55 of another substantially vertically slideable rod 56 which has a lateral lug or extension 57 at its upper end adapted to be engaged by the shoulder 51 of the key after the rod 46 has been depressed so that said key may slide the rod 56 upwardly and thereby cause the arm-engaging member 38 to swing to its open position of Figure 4 where it is engaged behind the shoulder 37 and thus retained set or inoperative. The rod 56 may be guided by a pin and slot connection 58 with the partition 11 and it may also be caused to tilt as it slides by means of a curved backing spring or strip 59 carried by the partition and engaging the adjacent edge of said rod 56 as shown, the tilting movement of the bar 56 being necessary in order to keep the lug 57 engaged with the shoulder 51 of the key when the latter is causing upward sliding movement of said rod 56.

In operation, a person desiring to turn in an alarm will grasp the handle or knob 9 and swing the disk closure 7 downwardly to the dotted line position of Figure 1 until the lug 19 causes closing of the circuit of the alarm 17 by the actuation of the circuit

closer 13. The person will then insert his arm into the tube 20 until the handle 22 of the switch 21 can be grasped and said handle 22 is then turned clockwise so as to cause 5 closing of the circuit of the second alarm 26 and to simultaneously release the catch 35 from the arm-engaging member 38 through the medium of the arms 27, 31 and 33, the links 34 and 28 and the shaft 32 hereinbefore described. The spring 40 will immediately cause the arm-engaging member 38 to be swung from the position of Figure 4 to the position of Figure 5 with the tooth 44 engaged with one of the teeth of the retaining member 42 and with the arm of the person effectively held in the tube 20 between the members 38 and 41. Upon arrival of an authorized person carrying the proper key 49, the arm of the person may be duly 20 released by causing the rod 46 to lower and simultaneously disengage the retaining member from the tooth 44 so that the person's arm is no longer positively held, further turning movement of said key causing 25 upward movement of the rod 56 and swinging of the arm-engaging member 38 again to the position of Figure 4 behind the shoulder 37 of the catch 35.

From the foregoing description, it is believed that the construction and operation of the present invention will be readily understood and appreciated by those skilled in the art.

Minor changes may be made without departing from the spirit and scope of the invention as claimed.

What is claimed as new is:

1. In an alarm box of the class described, a casing having front and rear vertical walls, the front wall of the casing being provided with a hand-hold, a rotary switch for an alarm circuit mounted upon the inner face of the rear wall of the casing in line with said hand-hold, a pivoted arm-engaging member normally urged to a position to engage and hold the arm of a person inserted within the casing through said hand-hold, means operatively connected to said switch for holding the arm-engaging member in inoperative position, said last

named means being operable upon turning of the switch to release said arm-engaging member, means to automatically engage the arm-engaging member and to retain the latter in engagement with the person's arm upon release of said arm-engaging member, said last named means including a pivoted toothed bar and key-operated means for releasing said toothed bar from the arm-engaging member, and key-operated means for swinging the arm-engaging member to inoperative position upon release of the same, said last named means including a member operable by the same key for releasing the toothed bar.

2. In an alarm box of the class described, a casing having front and rear vertical walls, the front wall of the casing being provided with a hand-hold, a rotary switch for an alarm circuit mounted upon the inner face of the rear wall of the casing in line with said hand-hold, a pivoted arm-engaging member normally urged to a position to engage and hold the arm of a person inserted within the casing through said hand-hold, means operatively connected to said casing for holding the arm-engaging member in inoperative position, said last named means being operable upon turning of the switch to release said arm-engaging member, means to automatically engage the arm-engaging member and to retain the latter in engagement with the person's arm upon release of said arm-engaging member, said last named means including a pivoted toothed bar and key-operated means for releasing said toothed bar from the arm-engaging member, and key-operated means for swinging the arm-engaging member to inoperative position upon release of the same, said last named means including a member operable by the same key for releasing the toothed bar and disposed to be actuated automatically subsequently to the release of the toothed bar upon continued turning of said key.

In testimony whereof we affix our signatures.

RUDOLPH ZAKRZEWSKI,
KAZIMIEZ SULEK.
